FISH BREEDING TANK

David D. Lovitz, Short Hills, N.J., assignor to Sternco Industries, Inc., Harrison, N.J., a corporation of New Jersey

Filed May 21, 1968, Ser. No. 12,030

Term of patent 14 years

Int. Cl. D30—01

U.S. Cl. D30—9

FIG. 1

FIG. 2

FIG. 3

FIG. 4

FIG. 5

FIG. 6

FIG. 7

FIGURE 1 is a front elevational view of a fish breeding tank showing my new design.

FIGURE 2 is a top plan view thereof.

FIGURE 3 is a side elevational view thereof, both sides being identical.

FIGURE 4 is a rear elevational view thereof.

FIGURE 5 is a bottom plan view thereof.

FIGURE 6 is a front elevational view of the cover and body portion of said fish breeding tank shown in disassembled relation.

FIGURE 7 is a side elevational view of the device as shown in FIGURE 6.

I claim:

The ornamental design for a fish breeding tank, as shown.
